MONEY TREE BANK

Stanley Tartar, 1235 27th St. N.,
Birmingham, Ala. 35200

Filed Mar. 26, 1971, Ser. No. 128,649

Term of patent 14 years

Int. Cl. D21—01

U.S. Cl. D34—11

FIG. 1

FIG. 3

FIG. 1 is a front elevational view of a money tree bank illustrating my new design;

FIG. 2 is a right side elevational view thereof; and,

FIG. 3 is a bottom plan view thereof.

I claim:

The ornamental design for a money tree bank, substantially as shown and described.
